UNITED STATES PATENT OFFICE.

DORR E. FELT, OF CHICAGO, ILLINOIS.

CALCULATING-MACHINE.

1,088,219.

Specification of Letters Patent. Patented Feb. 24, 1914.

Application filed September 1, 1911. Serial No. 647,171.

To all whom it may concern:

Be it known that I, DORR E. FELT, a citizen of the United States, residing in Chicago, in the county of Cook and State of Illinois, have invented a new and useful Improvement in Calculating-Machines, of which the following is a specification.

This invention relates to prime-actuating mechanism for that type of keyboard calculating-machines in which the register operates in immediate response to the manipulation of the key designating the values to be registered, without requiring the intervening manipulation of any other power-15 providing or power-controlling keys or levers.

One object of the invention is to provide a mechanism that will respond to exceedingly high-speed manipulation of the key-board and at the same time minimize the effort required to manipulate the keys.

Another object is to further this speeding of the action and lightening of the key-touch by efficiently devolving upon a continuously running power-motor work that in strictly key-driven machines is devolved upon the keys.

Another object has to simplify and render particularly positive the actuating mechanism of the type of key-board calculating-machines concerned. And the invention has for further objects such other improvements in structure and operation as may be found to obtain in the devices hereinafter described 35 or claimed.

A particular exemplification of the invention is embodied, for purposes of illustration, in the accompanying drawings, forming a part of this specification; but 40 the invention is of course not limited to such specific illustrative embodiment.

In said drawings, Figure 1 is a longitudinal section of a machine embodying my invention; Fig. 2 is a section on the line 2—2 45 of Fig. 1. Fig. 3 is a side view of a magnet for actuating the numeral wheel. Fig. 4 is a left-hand side-view of the escapement wheel for the numeral-wheel mechanism; and Fig. 5 is a like view of an accumulator 50 or numeral wheel. Fig. 6 is a section on the line 6—6 of Fig. 1. Fig. 6^a shows the escapements actuating and controlling the numeral wheel detached. Fig. 7 is a partial longitudinal section, taken in a plane adjacent to that of Fig. 1. Fig. 8 is a horizontal section on the line 8—8 of Fig. 7.

In said drawing 9 represents the top of a calculating machine, and 10, 10 represent the longitudinal plates separating the denominational trains of mechanism from each other. The denominational or column actuators are shown at 11 and they are pivoted at 12. The retracting or lifting springs are provided for each actuator as indicated at 13. The keys 14, of which there are nine in each denomination, are arranged in denominational rows, and are each adapted to be depressed by hand, and are also each provided with lateral projections 15 which, when the keys are actuated, engage the actuator of the denomination to which the keys belong and move such actuator downward a greater or less distance proportioned to the power of the keys. The keys are also provided with the usual individual lifting springs 16 by which they are retracted after each depressing operation.

The accumulator or numeral wheels of the machine are shown at 17, but it will be understood that these are a type of all the other numeral wheels embodied in the machine, and that all may be mounted on the numeral wheel shaft 18. Motion is transmitted and controlled between the column actuators and the numeral wheels by means of escapement mechanism which is certain and definite in its action, and at the same time never permits any overrunning by the wheels as illustrated in the drawings. The 90 column actuators at the front end, instead of being provided with gear teeth, are now provided with inverted V shaped teeth 25, the sides of which slope in opposite directions from the crowns to the bases, as shown, 95 and are adapted to impart impulses or rocking movements to the escapement device 26 which meshes with it, without effecting any arbitrary arrest of the actuator. This escapement 26 is such as is often found in anchor 100 escapements, and it is pivoted centrally upon a horizontal cross wire 24 and is provided at each end with pins or teeth 26^a which alternately enter the teeth of the actuator. A second escapement 23 is also 105 pivoted on the same wire 24 and is desirably made in one piece with escapement 26, and its office is to effect the turning of the numeral wheel of the denomination to which the actuator and the escapements belong. 110 This escapement 23, which may be fashioned as shown at Fig. 6^a and Fig. 7, is adapted

to engage with the star or escapement wheel 21 which is located on the numeral wheel shaft at the side of the numeral wheel and is rigidly attached to the latter. It is itself 5 loose upon the shaft but has a long hub or sleeve 22 upon which the numeral wheel is mounted, the numeral wheel itself thus having no contact with or attachment to the shaft. The teeth of the wheel 21 are such as 10 to insure rotation by it under the power of the magnet 20 hereinafter described, or such other device as may be employed for performing the function of such magnet, such rotations being measured by the escapement 15 23 and being due to and occurring whenever the escapement 26 receives an impulse or rocking movement from the column actuator. As the number of impulses given to 20 escapement 26 depends upon the movements 25 of the actuator, and is governed by the key which is struck, it will be seen that the number of impulses given the escapement 23 will also be in proportion to the power of the key and the consequent rotation of the 25 numeral wheel will be in the same proportion. A spring 40 is attached to the bar 41 uniting the two escapements 26 and 23 and supported from above on the cross wire 42, and tends to return the escapements after 30 each impulse received from the actuator.

In addition to the escapement mechanism described for transmitting and controlling motion between the column actuators and the numeral wheels, I also connect the numeral wheel shaft to a motor 19 by which that shaft will be continuously rotated in the direction required for adding when the machine is in use, and to utilize the power of such motor in moving the wheels. The 35 motor is desirably an electric one, such, for instance, as the one shown at 19, and it is desirably attached to the shaft as shown. I do not desire however to be limited to an electrical motor, nor to the attachment of 40 this motor directly to the shaft, as other kinds of motors may be used and they may be otherwise connected to the shaft. The ability to thus utilize the motor I obtain by the following means. Upon the numeral 45 wheel shaft, adjacent to each numeral wheel, I place permanent magnets 20 and secure such magnets to the shaft so that they will rotate continuously with the same, and between each magnet and its numeral wheel is 50 located the escapement wheel 21 already described.

With the construction above detailed, it will be noted that when the machine is in use, the shaft 18 is under constant motion, 55 and the magnets 20 are likewise constantly rotating. Also that the numeral wheels and escapement wheels 21 are always in the field of magnets 20, and are therefore constantly urged to rotate with them, but are restrained 60 from so doing by the escapements 23. The

escapements while normally restraining the numeral wheels against any rotation whatever, nevertheless do permit limited and measured rotations thereof when the escapements themselves are moved by the descending and rising movements of the actuators. Such limited and measured rotations of the numeral wheels take place during the movements of the escapements, and are proportioned to and governed by the extent of 70 the actuator movements. I have devised means whereby the movements of the actuators may be always proportioned to the power of the keys and these means are desirably constructed as follows: In each denominational space of the machine and above the actuator thereof, is a horizontal stop bar 27 having on its upper edge eight stops 28 preferably of the form shown, and each adapted to contact with the flat side of 75 the stems 29 of the keys 14, when the latter are depressed and the bar is moved forward, as stated below. The bars 27 are supported at their forward ends on the vertical members of elbow levers 30, pivoted at 31 to the 80 division plates 10, and at their rear ends upon the swinging arms 32 pivoted at 33 to the division plates. The horizontal members of the elbow levers are each connected to the corresponding actuators by links 34. With 85 this construction, it will be noted that when any one of the first 8 keys is depressed, the actuator will through the elbow lever cause a forward movement of the bar 27, and this movement will bring the stop 28, corresponding to the key which has been struck, against the stem of that key and cause an instant stoppage of the downward movement of the actuator. This arrest takes 90 place in every case when the stop encounters 95 the key so that the amount of movement given the actuator will depend in every case upon the power of the key and never exceed the power, the one key causing the arrest very quickly, the two key somewhat later, 100 the three key still later, and so on through the series of eight keys. The nine key when depressed is carried to the bottom of its path and hence needs no regulation, so no stop 28 is provided for it as in the case of 105 the other keys. As the segment teeth 25 are adapted to give a greater or less number of impulses to the escapements 26, depending upon the extent to which the actuators are depressed, and as the escapements 23 110 move with escapements 26 and receive a corresponding number of impulses, it will be seen that the numeral wheels will necessarily be rotated correspondingly to the power of the keys which have been struck. 115 The rotary movements of the numeral wheels are by the means described caused one half by the descending movements of the actuators, and one half by their ascending movements, and in them the escape- 120

ments 26 control the escapements 23 and thereby measure the rotation permitted to the numeral wheels.

While I have indicated permanent magnets 20 as being secured on the numeral wheel shaft in close relation to the numeral wheels so that they can rotate the latter whenever the locking action on them is released, yet I do not wish to be limited to such magnets for that purpose as obviously other devices performing the same function can be substituted for the magnets. It will also be noted that the star wheel 21 has lateral projections 50 on the side of each tooth 15 nearest the magnet. These enable the concentration of the lines of force from the magnet upon the outer part of the wheel where they are most effective. It will also be noted that while transfer mechanism is 20 not shown, in the drawings, between the denominational trains of prime-actuating mechanism, the transfer of tens may of course be effected by, for instance, means causing the escapement 23-26 to rock once 25 when the numeral-wheel of next lower denomination has made a revolution, since one rocking movement of any escapement results in a one-step advance of the corresponding numeral-wheel, thereby adding one to its reading. It is further to be noted that the continuously rotating magnet shown in the drawings runs normally free of, and without frictional wear upon, the accumulator wheel that it tends to drive.

35 I claim:—

1. In a calculating machine, the combination with a denominational series of keys, a column actuator receiving varying amounts of movement from said keys, and a numeral 40 wheel, of escapement devices controlling the numeral wheel and themselves controlled by the actuator.

2. In a calculating machine, the combination with the numeral wheel, of a column actuator having a toothed segment and adapted to be depressed by keys, and escapement devices whereby the actuator controls the movements of the wheel.

3. In a calculating machine, the combination with a denominational series of keys, a column actuator receiving varying amounts of movement from said keys, and a numeral wheel, of an escapement receiving impulses from teeth upon the actuator, 55 and a second escapement operated by the first one and controlling the numeral wheel.

4. In a calculating machine, the combination with a denominational series of keys, a column actuator receiving varying amounts 60 of movement from said keys, and a numeral wheel, of an escapement receiving its impulses from teeth upon the actuator, and a second escapement rigid with the first one, and acting to control the numeral wheel.

65 5. In a calculating machine, the combina-

tion with a denominational series of keys, an actuator receiving varying amounts of movement from said keys, and an accumulator wheel, of a continuously rotating magnet on the shaft of the accumulator wheel, 70 tending to rotate the wheel, an escapement receiving impulses from teeth upon the actuator, and a second escapement controlling the numeral wheel and operated by the first mentioned escapement. 75

6. In a calculating machine, the combination with a denominational series of keys, a column actuator receiving varying amounts of movement from said keys, and an accumulator wheel, of a continuously rotating 80 magnet on the shaft of the accumulator wheel always tending to rotate the wheel, and escapement devices controlling the accumulator wheel, such escapement devices normally locking the accumulator wheel except during the proper movement of the escapement. 85

7. The combination in a calculating machine, of an accumulator wheel, a column actuator imparting varying amounts of 90 movement to said wheel, a motor connected to the shaft of said wheel and continuously rotating the same, means normally free of said wheel and tending to rotate it with the shaft, means for preventing normal rotation of the wheel with the shaft, means for releasing the wheel, and means whereby the actuator determines the extent of the rotations allowed the wheel. 95

8. The combination in a calculating machine, of an accumulator wheel, a column actuator imparting varying amounts of movement to said wheel, a motor connected to the shaft of said wheel and continuously rotating the same, means normally free of 105 said wheel and tending to rotate it with the shaft, means for preventing normal rotation of the wheel with the shaft, means for releasing the wheel, and escapement mechanism controlled by the actuators for determining the extent of the rotations allowed 110 the wheel.

9. The combination in a calculating machine, of an accumulator wheel, a column actuator imparting varying amounts of 115 movement to said wheel, a motor connected to the shaft of said wheel and continuously rotating the same, means normally free of said wheel and tending to rotate it with the shaft, a series of keys determining the action of the actuator, means for arresting the keys at the ends of their stroke, and escapement mechanism for determining the extent of the rotations allowed the wheel. 120

10. The combination in a calculating machine, of an accumulator wheel, a column actuator imparting varying amounts of movement to said wheel, a motor connected to the shaft of said wheel and continuously 125 rotating the same, means normally free of 130

said wheel and tending to rotate it with the shaft, a series of keys determining the action of the actuator, an escapement preventing normal rotation of the wheel with the shaft, and means for releasing the wheel.

11. The combination in a calculating machine, of an accumulator wheel, a column actuator and keys imparting varying amounts of movement to said wheel, a motor connected to the shaft of said wheel and continuously rotating the same, an escapement preventing normal rotation of the wheel with the shaft, and a second escapement controlled by the actuator for determining the extent of the rotations allowed to the wheel.

12. The combination in a calculating machine, of a numeral wheel, a column actuator and keys imparting varying amounts of movement to said wheel, a motor connected to the shaft of said wheel and continuously rotating the same, an escapement preventing normal rotation of the wheel with the shaft, and a second escapement controlled by the actuator for determining the extent of the rotation allowed to the wheel, said last mentioned escapement actuating the first mentioned one and causing the release of the wheel and also determining the extent of the rotation allowed to the wheel.

13. The combination in a calculating machine, of a numeral wheel, a column actuator and keys imparting varying amounts of movement to said wheel, a motor connected to the shaft of said wheel and continuously rotating the same, an escapement preventing normal rotation of the wheel with the shaft, and a second escapement controlled by the actuator for determining the extent of the rotation allowed the wheel, said escapements being united and the last mentioned one actuating the first mentioned one and causing the release of the wheel and also determining the extent of the rotations allowed to the wheel.

14. The combination in a calculating machine, of an accumulator wheel, a column actuator and keys imparting varying amounts of movement to said wheel, a motor connected to the shaft of said wheel and continuously rotating the same, an escapement preventing normal rotation of the wheel with the shaft, and a second escapement controlled by the actuator for determining the extent of the rotations allowed to the wheel, said escapements being pivoted on a common axis and united so that one may control the other.

15. The combination in a calculating machine, of an accumulator wheel, a shaft on which the wheel is mounted, a motor acting to rotate the shaft continuously, a magnet made fast on the shaft, an escapement wheel fast to the accumulator wheel and constantly under tension from the magnet, an escape-

ment driving said escapement wheel, the keys and means whereby the movements permitted to said escapement wheel are proportioned to the movements of the keys.

16. The combination in a calculating machine, of a denominational series of keys, an accumulator wheel, a shaft for said wheel, means for rotating said shaft continuously, means normally preventing said wheel from rotating with the shaft, means normally free of said wheel and tending to rotate it with the shaft, means for controlling said restraining means and allowing measured rotating movements by the wheel, and means whereby the keys determine the extent of such rotations.

17. The combination in a calculating machine, of an accumulator wheel, a continuously driven shaft on which the accumulator wheel is mounted, a magnet fast on said shaft, an escapement wheel rigid with the accumulator wheel, and located at the side of and constantly acted upon by the magnet, a column actuator adapted to be depressed by the hand, and having a toothed segment at its front end, an escapement operated by said segment and secured to and operating simultaneously with said first mentioned escapement, and means for arresting the column actuator when it has moved to the extent of the power of the key struck.

18. The combination in a calculating machine, of an accumulator wheel, a continuously driven shaft on which the accumulator wheel is mounted, a magnet fast on said shaft, means normally preventing the wheel from rotating with the magnet, means for releasing the accumulator wheel from such restraint, a column actuator causing action by the releasing means, a stop bar regulating the extent of action by the releasing means, and a motor for actuating the accumulator wheel shaft.

19. In a calculating machine, the combination with the accumulator wheel, of a device fast on the shaft of said wheel and continuously rotating in one direction and exerting tension on the wheel, and a column actuator adapted to be depressed by the keys, escapement devices whereby the actuator controls the numeral wheel, such wheel being actuated by power from said tension device during the movement of the actuator.

20. The combination with the denominational series of keys, the column actuator driven and controlled by the keys, and the numeral wheel of the same denomination with the keys and actuator, of escapement devices whereby the actuator controls the numeral wheel, and stops limiting the varying strokes of the keys in proportion to their respective values.

21. The combination with a denominational series of keys, an accumulator wheel,

a column actuator adapted to be depressed by said keys, stops limiting the strokes of the keys and arresting the actuator when the limit is reached, escapement devices where-
 5 by the actuator gives motion to the accumu-
 lator wheel, and acting also to normally re-
 strain the wheel from moving with its shaft,
 means for continuously rotating the shaft of
 the accumulator wheel, and means whereby
 10 the wheel is momentarily released and al-
 lowed to turn with the shaft proportion-
 ately with the power of the key struck.

22. In a multiple-order key controlled calculating-machine, the combination with a
 15 denominational series of the keys and a column actuator therefor, of a stop bar ar-
 ranged at the side of the keys and mechani-
 cally connected to the actuator, and having
 20 separate stops one for each key, and each
 adapted to contact with the stem of the key
 to which it corresponds, and thereby to ar-
 rest the actuator when it reaches the limit
 of the key's stroke.

23. In a multiple-order key controlled cal-
 25 culating-machine, the combination with a
 denominational series of the keys, and a column actuator therefor, of a horizontally
 reciprocating stop bar arranged at the side
 30 of the keys and mechanically connected to
 the actuator, and having separate stops one
 for each key, and each adapted to contact
 with the stem of the key to which it corre-
 sponds, and thereby to arrest the actuator
 35 when it reaches the limit of the key's stroke.

24. In a multiple-order key controlled calculating-machine, the combination with a
 40 denominational series of the keys, and a column actuator therefor, of a stop bar ar-
 ranged at the side of the keys and mechani-
 cally connected to the actuator by an elbow
 lever and link, and having separate stops
 45 one for each key, and each adapted to con-
 tact with the stem of the key to which it cor-
 responds, and thereby to arrest the actuator
 when it reaches the limit of the key's stroke.

25. In prime-actuating mechanism for a calculating machine, in combination: nu-
 50 meral-wheel mechanism; a driven member
 therefor, normally restrained from move-
 ment; a driving magnet tending to drive
 said driven member; a motor continuously
 impelling said magnet; means for releasing
 55 said driven member and variously limiting
 its movements; and a denominational series
 of keys severally effecting such release and
 limitation of movement of the magnetically
 impelled driven member; whereby the con-
 60 tinuously running motor normally free of
 the numeral-wheel mechanism effects its
 varying movements in immediate response
 to the actuating of the denominational keys;
 substantially as specified.

26. In prime-actuating mechanism for a calculating-machine, in combination: nu-
 65 meral-wheel mechanism; a driven member
 therefor, normally restrained from move-
 ment; a driving member normally free of
 said driven member; a motor continuously
 impelling said driving member; means for
 70 permitting said driving member to drive
 said driven member to variously limited ex-
 tents; and a denominational series of keys
 severally effecting the release and limiting
 the movements of said driven member;
 75 whereby the continuously running motor
 normally free of the numeral-wheel mecha-
 nism effects its varying movements in im-
 mediate response to the actuating of the de-
 nominational keys; substantially as specified.

27. In prime-actuating mechanism for a
 80 calculating-machine, in combination: nu-
 meral-wheel mechanism; a column-actuator;
 and a column of keys for variously actuating
 said column-actuator in proportion to their
 85 respective values; said column-actuator be-
 ing provided with a stop device including a
 series of stops moving with the column-actu-
 ator and stopping it by respectively encoun-
 tering and being blocked by the keys at the
 conclusion of their proper active strokes, to
 90 limit the varying key-driven movements
 of the column-actuator, substantially as
 specified.
